UNITED STATES PATENT OFFICE.

PETER F. McCAFFREY, OF SPOKANE, WASHINGTON.

SIPHON FLUSH-VALVE.

1,302,820.

Specification of Letters Patent.

Patented May 6, 1919.

Application filed September 25, 1917. Serial No. 193,168.

To all whom it may concern:

Be it known that I, PETER F. McCAFFREY, a citizen of the United States, residing at Spokane, in the county of Spokane and State 5 of Washington, have invented a new and useful Siphon Flush-Valve, of which the following is a specification.

The device forming the subject matter of this application is a flush tank, and the invention aims to provide novel means for starting the flow of water from the tank and for controlling the flow of water.

It is within the province of the disclosure to improve generally and to enhance the 15 utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within 20 in the scope of what is claimed, without departing from the spirit of the invention.

In the accompanying drawings:

Figure 1 is a vertical section taken through a flush tank embodying the present invention, parts appearing in elevation;

Fig. 2 is a perspective view showing the valve mechanism;

Fig. 3 is a vertical section taken through the valve mechanism disclosed in Fig. 2;

Fig. 4 is a fragmental horizontal section illustrating one of the shafts and attendant parts; and

Fig. 5 is a fragmental vertical section illustrating a modified form of the invention, parts appearing in elevation;

Fig. 6 is a vertical section taken through a flush tank embodying a modification in the present invention, parts appearing in elevation;

Fig. 7 is a vertical section taken through the valve mechanism used in connection with that form of the invention which is delineated in Fig. 6;

Fig. 8 is a fragmental horizontal section showing the shaft and attendant parts, as used in Fig. 6.

The numeral 1 designates a flush tank.

The numeral 2 marks a siphon including an intake leg 3 and an outlet leg 4. The outlet leg 4 opens through the bottom of the flush tank 1. A water supply pipe 5 opens through the bottom of the flush tank 1 and carries at its upper end, a valve casing 6 having a seat 7 in its interior. The casing 6 is supplied with a lateral tubular extension 8 connected with a depending outlet pipe 9 discharging into the tank 1. A connecting pipe 10 leads from the side of the extension 8 to the crown of the siphon 2 and discharges into the outlet leg 4. A hollow valve 11 is journaled in the extension 8 and has a side port 51 adapted to be brought into registration with the pipes 9 and 10. A cap 12 is secured to the outer end of the valve 11 and overhangs the outer end of the extension 70 8, the cap being provided with a finger 14 adapted to move between and contact with radial projections 15 and 16 on the extension 8 of the casing 6. The cap 12 has a radial arm 17. A rod 18 is pivoted to the arm 17 75 and is pivoted to an arm 19 carried by a sleeve 23 having an arm 22. The sleeve 23 is secured by a set screw 24, for adjustment, to a shaft 20 journaled in the walls of the tank 1. The shaft 20 is provided with a handle 21 located exteriorly of the tank 1 and constituting a means whereby the shaft 80 may be rotated. A suspension element, such as a rod 25, is pivoted at its upper end to the arm 22, the lower end of the member 25 being pivoted to a rod 26 extended across a bucket 27. The numeral 28 denotes an arm terminating in a fork 29, the arm constituting a part of a sleeve 30 which is adjustable on the shaft 20, the sleeve being held in 90 place by a set screw 31.

The numeral 32 denotes a float connected to one end of a rod 33. A bar 34 is provided, the bar 34 and the rod 23 being provided with toothed heads 35 held in contact adjustably by means of a bolt and wing nut 36. The bar 34 is fulcrumed at 37 in a fork 38 constituting a part of the casing 6, the parts 34 and 33 constituting a float lever. The upper end of a link 39 is pivoted to one end of the bar 34, the lower end of the link being pivoted to a lever 40 mounted to move within the fork 38 and fulcrumed at 41 on a bracket 42 constituting a part of the casing 100

6. A valve 43 coöperates with the seat 7 and moves vertically in the casing 6, the valve having an opening 44 through which the lever 40 passes, so that the valve can be 5 actuated by the lever.

When it is desired to flush the tank 1, the handle 21 is swung in a clockwise direction, thereby rotating the shaft 20. When the shaft 20 is rotated, the arm 19 moves the rod 10 18 endwise, and rotation is imparted to the valve 11 by way of the cap 12 and the arm 17, the finger 14 engaging the projection 16 on the extension 8 of the casing 6. When the valve 11 is rotated as aforesaid, the port 15 51 in the valve will be brought into registration with the pipe 10.

When the shaft 20 is rotated as above described by means of the handle 21, the fork 29 on the arm 28 depresses the float lever 20 33—34, the same swinging on its fulcrum 37. The link 39 imparts movement to the lever 40 and the latter raises the valve 43 off the seat 7. Water traversing the supply pipe 5 enters the valve casing 6 and the valve 11, 25 the water passing out of the valve 11 by way of the port 51 into the pipe 10. From the pipe 10 the water flows downwardly into the outlet leg 4 of the siphon 2. This operation reduces the pressure in the crown of 30 the siphon below atmospheric pressure, and the atmospheric pressure on the water outside of the siphon causes the water to start to flow downwardly through the leg 4, water being siphoned out of the tank 1 in this way.

35 When the shaft 20 is rotated by means of the handle 21 as aforesaid, the arm 22 and, consequently, the bucket 27 are elevated. It is to be observed that so long as the bucket 27 is submerged in the water in the tank, the 40 bucket has no appreciable weight. When, however the level of the water in the tank falls below the bucket 27, then the water in the bucket gives an added increment of weight thereto.

45 When the water, having been siphoned out of the tank 1, has fallen sufficiently, and when the float 32, following the water, has moved downwardly to a predetermined point, the rod 33 no longer bears on the fork 50 29 of the arm 28. Then the shaft 20 is rotated by the weight of the bucket 27 and its contents, the handle 21, the arm 22, the arm 19 and the arm 28 being restored to positions of Fig. 1. When this operation takes 55 place, the rod 18 rotates the valve 11 by way of the cap 12 and the arm 17, until the port 51 in the valve is out of registration with the pipe 10 and is in registration with the pipe 9. Water flowing upwardly through 60 pipe 5, the casing 6 and the valve 11 is discharged through the pipe 9 into the tank 1 and fills the tank. As the water accumulates in the tank, the float 31 rises, tilting the lever 33—34 and closing valve 43 on the seat 7, 65 by means of the link 39 and the lever 40.

The supply of water to the tank through the pipe 5, the casing 6, the valve 11, the port 51 and the pipe 9 thus is cut off.

In Fig. 5 of the drawings, a slight modification of the invention is shown. In Fig. 70 5, the numeral 45 denotes a tank and the numeral 46 denotes a siphon, comprising an outlet leg 47 assembled with the bottom of the tank, and an intake leg, in the form of a cap 48 inverted over the outlet leg 47. A 75 pipe 49 enters the top of the cap or intake leg 48 and discharges into the outlet leg 47 of the siphon. The pipe 49 corresponds to the pipe 10 mentioned in connection with the preferred form of the invention. A vent 80 pipe 50 may open through the top of the cap 48, the pipe 50 terminating at its lower end, adjacent to the bottom of the tank 45. The function of the pipe 50 is to prevent the water from being siphoned out of the tank 85 45 beyond a level represented by the lower end of the pipe 50. The pipe 50, if desired, may be omitted. It will be obvious that the structure shown in Fig. 5 contemplates merely a change in the form of the siphon, 90 the general operation of the device being unaffected.

In Figs. 6, 7 and 8, a modified form of the invention is shown. In the said figures, parts hereinbefore described have been 95 designated by numerals previously used, with the suffix "a". The modification in this form of the invention consists in omitting the extension 8 on the valve casing 6, the pipe 10, the rotary valve 11, the actuating 100 rod 18 and the arm 19 on the shaft 20.

In the form of the invention shown in Figs. 6 to 8 both inclusive, the handle 21^a is swung in a clockwise direction, rotating the shaft 20^a. The fork 29^a on the arm 28^a 105 engages the float lever 33^a—34^a and tilts the same on its fulcrum 37^a, thereby depressing the float 32^a, elevating the valve 43^a off the seat 7^a, and elevating the bucket 27^a. The water flows from the pipe 5^a through the 110 pipe 9^a from the casing 6^a and, rising in the tank 1^a, starts the siphon 2^a. In this connection it is to be observed that the form shown in Figs. 6, 7 and 8 is adapted to be used especially when there is a high pressure in 115 the main which supplies the pipe 5^a. When the water in the tank 1^a falls below the level of the bucket 27^a after the latter has been raised, the weight of the water in the bucket 27^a becomes effective to restore the shaft 20^a 120 and its parts to the positions shown in Fig. 6.

Having thus described the invention, what is claimed is:—

1. In a device of the class described, a 125 flush tank; a siphon communicating with the tank and discharging therefrom; a source of water supply for the tank having an outlet discharging into the tank; a valve controlling said source; a float operatively 130

connected with the valve; a conduit discharging from said source into the siphon adjacent its crown; a single valve controlling the flow of water from the source

5 into the outlet and into the conduit; and means under the control of an operator and assembled with the last specified valve and at times under the control of the float for actuating the said valve to direct the water 10 from the source into the outlet and into the conduit at different times.

2. In a device of the class described, a flush tank; a siphon communicating with the tank and discharging therefrom; a source of 15 water supply for the tank having an outlet discharging into the tank; a valve controlling said source; a float operatively connected with the valve; a conduit discharging from said source into the siphon adjacent its crown; a second valve controlling the flow of water from the source into the outlet and into the conduit; a rocking structure movable from an initial position by an operator and including means for depressing 20 the float to actuate the first specified valve; a bucket assembled with the rocking structure for returning the same to said initial position after the float has descended 25

out of engagement with the means for depressing the float; and means for operatively connecting the rocking structure with the second valve. 30

3. In a device of the class described, a flush tank; a siphon communicating with the tank and discharging therefrom; a source of water supply for the tank having an outlet discharging into the tank; a valve controlling said source; a float operatively connected with the valve; a rocking structure movable from an initial position by an operator and including means for depressing the float thereby to open the valve; and a bucket assembled with the rocking structure for returning the same to said initial position after the float has descended out of engagement with the means for depressing the float and after the level of the water in the tank has fallen below the level of the bucket. 35 40 45

In testimony that I claim the foregoing as my own, I have hereto affixed my signature 50 in the presence of two witnesses.

PETER F. McCAFFREY.
